UNITED STATES PATENT OFFICE

123,235

DESIGN FOR A BOTTLE

Franz Neuschaefer, Rye, N. Y.

Application February 5, 1940, Serial No. 90,061

Term of patent 7 years

To all whom it may concern:

Be it known that I, Franz Neuschaefer, a citizen of the United States and a resident of Rye, in the county of Westchester and State of New York, have invented a new, original, and ornamental Design for a Bottle, of which the following is a specification, reference being had to the accompanying drawing, forming a part thereof, wherein:

Figs. 1, 2 and 3 respectively are front, back and side elevational views, and Fig. 4 is a top view of a bottle showing my new design.

I claim:

The ornamental design for a bottle, substantially as shown.

FRANZ NEUSCHAEFER.
